CLAIM

The ornamental design for a bottle, as shown and described.

DESCRIPTION

FIG. 1 is a front, right-side, and top isometric view of a bottle showing the new design.

FIG. 2 is a front elevation view of the bottle.

FIG. 3 is a rear elevation view of the bottle.

FIG. 4 is a right-side elevation view of the bottle.

FIG. 5 is a left-side elevation view of the bottle; and,

FIG. 6 is a top plan view of the bottle.

The broken lines depict portions of the bottle that form no part of the claimed design.
